United States Patent Office

Des. 232,176
Patented July 23, 1974

232,176

FAN

George T. Brockman, Stoddard, Richard W. Kabat,
Genoa, and Ronald J. Lievens, Onalaska, Wis., as
signors to The Trane Company, La Crosse, Wis.

Filed May 8, 1972, Ser. No. 251,574

Term of patent 14 years

Int. Cl. D23—04

U.S. Cl. D23—162

FIG. 1

FIG. 2

FIG. 3

FIG. 4

FIG. 5

FIG. 1 is a perspective view of a fan showing our new design.

FIG. 2 is a side elevational view thereof.

FIG. 3 is a front elevational view thereof.

FIG. 4 is a side elevational view thereof of the side opposite that shown in FIG. 2.

FIG. 5 is a rear view thereof.

We claim:

The ornamental design for a fan, as shown.
